UNITED STATES PATENT OFFICE.

HERBERT J. PRICE, OF AMESBURY, MASSACHUSETTS.

CAR-SEAL.

No. 837,505.

Specification of Letters Patent.

Patented Dec. 4, 1906.

Application filed April 19, 1906. Serial No. 312,604.

To all whom it may concern:

Be it known that I, HERBERT J. PRICE, a citizen of the United States, residing at Amesbury, in the county of Essex and State 5 of Massachusetts, have invented certain new and useful Improvements in Car-Seals; and I do declare the following to be a full, clear, and exact description of the invention, such as will enable others skilled in the art to 10 which it appertains to make and use the same.

This invention relates to improvements in car-seals.

The object of the invention is to provide a 15 seal for freight-cars and the like which may be quickly applied to the same and which may be also used for sealing valuable packages of any kind.

Another object is to provide a seal constructed of a comparatively inexpensive material and so arranged as to be closed without the use of an especially-constructed instrument and which when closed will be reliable and secure.

With the above and other objects in view the invention consists of certain novel features of construction, combination, and arrangement of parts, as will be hereinafter described and claimed.

In the accompanying drawings, Figure 1 is a plan view of the front side of the seal, showing the same in closed position. Fig. 2 is a similar view of the opposite side. Fig. 3 is a plan view of the inner side of the back disk. Fig. 4 is a similar view showing the arrangement of the wire loop therein before the ends of the latter are engaged and fastened. Fig. 5 is a sectional view of the seal with the ends of the wire engaged, but not 35 clenched. Fig. 6 is a similar view showing the ends of the wire clenched; and Fig. 7 is a detail perspective view of the wire loop used in connection with the seal, showing the ends of the wire connected in full lines and disconnected in dotted lines.

Referring more particularly to the drawings, 1 denotes the seal, which consists of front and rear plates or disks 2 and 3. The front disk 2 has formed around its edge an 50 annular clenching-flange 4, whereby when said disks are engaged the flange 4 is tightly clenched around the edge of the rear disk, thereby securely fastening the two disks together.

In the rear disk 3 is formed a substantially U-shaped groove 5, the ends of which open

through one side or edge of the disk, as shown. One of the arms of the groove 5 is increased in width to form a recess 6, said recessed end of the groove being provided with a depression 7, the purpose of which will hereinafter appear.

Adapted to be used in connection with the disks 2 and 3 is a wire-fastening loop 8, one end of which is bent upon itself to form 65 a substantially U-shaped loop which conforms to and is adapted to be engaged with the groove 5 in the rear disk 3. The end of the bent or looped portion of the disk has formed thereon a hook 9, which when the 70 looped end of the wire is inserted in the groove 5 is adapted to engage the depression 7 in the recess 6 in said groove, as clearly shown in Figs. 5 and 6 of the drawings. The looped or U-shaped end of the wire is adapt- 75 ed to be held in the groove 5 by the front plate of the disk when said plates or disks are clenched together. The flange 4 of the front plate is cut away where the same engages the wire passing into the groove 5 and 80 is also cut away opposite the recess 6 in the lower disk to provide a passage for the opposite end of the wire-fastening loop. The opposite end of the wire-fastening loop is provided with an eye 10, which after the loop 85 has been engaged with an article to be sealed is inserted through the passage in the flange 4 and through the recess 6 in the end of the groove 5 and is engaged with the open hook 9 on the opposite end of the wire. After the 90 eye 10 has been thus engaged with the hook 9 said hook is closed by pressure applied to the opposite sides of the disks 2 and 3 above and below the hook. The necessary pressure may be applied to the hook 9 95 through the disks 2 and 3 by an ordinary pair of pliers or any suitable instrument, and when thus closed the eye cannot become disengaged or the loop of the wire opened without cutting said wire or mutilating the disk, 100 which will indicate that the seal has been tampered with.

A seal constructed as herein shown and described may be formed of inexpensive material, the disks 2 and 3 being constructed of tin or a cheap grade of sheet metal, which will reduce the cost of manufacture over the common construction of seals formed of lead or other malleable metal.

From the foregoing description, taken in 110 connection with the accompanying drawings, the construction and operation of the inven-

tion will be readily understood without requiring a more extended explanation.

Various changes in the form, proportion, and the minor details of construction may be resorted to without departing from the principle or sacrificing any of the advantages of this invention as defined by the appended claims.

Having thus described my invention, what I claim as new, and desire to secure by Letters Patent, is—

1. A seal comprising front and rear sheet-metal disks, means for securing said disks together, a U-shaped groove formed in one of said disks, a wire-fastening loop having one end bent upon itself to form a U-shaped loop to lie in said groove, a hook formed on said bent end of the wire, and an eye formed on the opposite end of said wire to engage said hook between said disks.

2. A seal comprising a pair of sheet-metal disks, means for securing said disks together, an approximately U-shaped groove formed in one of said disks and having a depression formed in one wall thereof, a fastening-loop having one end bent to conform to the U-shaped groove and adapted to lie therein, a hook on the bent end of said loop to engage the depression in the wall of said groove, and an eye on the other end of the loop to engage

said hook, said hook being closed upon said eye by pressure exerted on the outer faces of the disks.

3. A car-seal comprising a front disk and a rear disk formed of sheet metal, an annular flange formed around the edge of said front disk to engage the edge of said rear disk, whereby said disks are clenched together, a U-shaped groove formed in said rear disk, said groove having a recess and a depression formed therein, a wire-fastening loop having one end bent to conform to the shape of the U-shaped groove in said disk, whereby said bent end of the wire is secured between said disks, a hook formed on the bent end of the wire and engaged with the depression in the recess of said groove, and an eye formed on the opposite end of the wire to engage the hook on the bent end of the same, said hook being adapted to be closed upon said eye by pressure on the outer sides of said disks, substantially as described.

In testimony whereof I have hereunto set my hand in presence of two subscribing witnesses.

HERBERT J. PRICE.
